IMPROVEMENT IN INSTRUMENTS FOR DESTROYING EMBRYO CATERPILLARS.

AARON CASEBEER, OF SIPESVILLE, PENNSYLVANIA.

Letters Patent No. 60,136, dated December 4, 1866.

SPECIFICATION.

TO ALL WHOM IT MAY CONCERN:

Be it known that I, AARON CASEBEER, of Sipesville, in the county of Somerset, and State of Pennsylvania, have invented an Instrument for Destroying the Embryo of Caterpillars; and I do hereby declare that the following is a full, clear, and exact description thereof, reference being had to the accompanying drawings, making a part of this specification, in which—

Figure 1 is a perspective view, showing the manner of using the instrument.

Figure 2 shows the manner of securing the cutting blades to a staff.

Figure 3 is a front view of the cutting blades applied to the upper end of their staff.

Similar letters of reference indicate corresponding parts in the several figures.

This invention relates to an improved instrument which is designed for destroying the eggs of the caterpillar by removing those portions of the branches and twigs of trees to which the eggs are attached. The invention consists in so constructing a knife and applying it to a staff that small branches of trees can be readily cut off by a thrust or drawing movement of the staff, whether the person be above or below such branches, said knife being so applied to its staff that the twig or branch will be held firmly at the point where it is desired to sever it, as will be hereinafter described.

To enable others skilled in the art to understand my invention, I will describe its construction and operation.

The staff of the instrument is constructed of any desired length, and may be made of detachable sections, so that it may be shortened or made longer, as circumstances require. Near the upper end of this staff, A, and on one side of it, the knife, B, is applied by means of bolts, a a, passing through the staff and receiving nuts on their ends, as shown in fig. 2. The knife consists of two blades, C C, formed on the central shank, b. These cutting blades are both alike in form, and are bevelled, so that their cutting edges are nearest the staff. The cutting edges of the knives form acute angles with the surface of the staff, so that the branches which are to be cut off are received in the V-shaped spaces, and consequently cannot slip away from the cutting edges during the act of severing. Two blades, C C, are used for the purpose of enabling a person to cut branches from their limbs which are above and below him, as in some cases it will be necessary to ascend the trees for the purpose of reaching those limbs or branches which have the eggs attached to them. When the upper blade is used the branch is cut off by a thrust of the instrument; and when it is necessary to use the lower knife the instrument is drawn quickly toward the person using it.

Having thus described my invention, what I claim as new, and desire to secure by Letters Patent, is—

A knife which is composed of two blades, C C, united to a contracted shank, b, to be used substantially as described.

AARON CASEBEER.
